UNITED STATES PATENT OFFICE.

HARRISON GINDELE, OF CINCINNATI, OHIO.

DEVELOPING APPARATUS.

1,256,893.

Specification of Letters Patent. Patented Feb. 19, 1918.

Application filed September 5, 1914. Serial No. 860,431.

To all whom it may concern:

Be it known that I, HARRISON GINDELE, a citizen of the United States, residing at Cincinnati, in the county of Hamilton and State of Ohio, have invented certain new and useful Improvements in Developing Apparatus; and I do hereby declare the following to be a full, clear, and exact description of the invention, such as will enable others skilled in the art to which it appertains to make and use the same.

This invention is a photographic apparatus which is herein termed a developing negative carrier, and is particularly adapted for the development of sensitized plates, although it is obvious that it can be employed for the development of films.

One purpose of the invention is to provide a device in which photographic plates may be developed by daylight without the necessity of entering a dark room, the plate being prevented from exposure to light rays.

An aim of the invention is to provide a light proof-receptacle of small dimensions for a plurality of sensitized plates or films which may be immersed in solutions to act upon the emulsion of the plates, and permit of their development, fixation and washing while confined in the receptacle, thereby eliminating handling each individual plate or film, with resultant tendency to injury to the negative, and at the same time relieve the operator of the necessity of placing his hands in contact with the various solutions as they are applied to the negative subject.

It is well known that those constantly engaged in the development of sensitized photographic negatives or prints are subject to diseases of the cuticle caused by some of the chemicals employed during the developing process. Moreover, in the manner of developing each plate or film in an open tray within a dark room, the sensitized surface is frequently scratched or injured while the sensitized emulsion is soft, due to frequent handling of the plates or films during their individual examination and transfer to the various fluid baths.

The invention embodies a separable device to permit of proper cleaning and drying of the holder after use, the various elements being arranged in compact form to receive and retain a plurality of exposed subjects in separate compartments protected from exposure to light, and free

from injury by manual manipulation. The negative carrier is preferably of a size substantially the same, or but a little larger than a plate holder for a predetermined size plate, and is designed to receive the exposed plate or film from the plate holder. A plurality of plate developing carriers may be immersed in a single bath, such as that prepared for the time development method, transferred to washing vats, thence to fixing baths and thence to washing and drying receptacles without removing the plates from the carrier. The various baths and vats may be in an ordinary room and exposed to daylight or artificial light, as the exposures are protected by the carrier from injury by light. Further objects and advantages of the invention will become apparent from the following detailed description, taken in connection with the accompanying drawings.

One embodiment of the invention is disclosed in the drawings, but it is to be understood that such disclosure is for the purpose of illustration only, and not as defining the limits of the invention.

In the drawings:—

Fig. 1 is a perspective view of an upper section of the negative developing carrier, said section being removed from the carrier;

Fig. 2 is a perspective view of the central body portion of a negative carrier, said body portion being removed from the frame;

Fig. 3 is a perspective view of the base section of the negative carrier, said section being removed from the body portion of Fig. 2;

Fig. 4 is a perspective view of the outer frame member of the developing carrier, which frame member receives the sections disclosed in Figs. 1, 2 and 3;

Fig. 5 is a detail perspective view of one of the slides for the developing negative carrier;

Fig. 6 is a longitudinal sectional view through the upper section of the plate carrier illustrated in Fig. 1;

Fig. 7 is a vertical sectional view through the developing plate carrier, the parts of Figs. 1, 2, 3 and 4 being assembled, and with one of the slides at Fig. 5 removed therefrom.

In the embodiment of the invention here-

in illustrated, the plate developing carrier is shown having a plurality of compartments, each protected by removable slides, similar to those employed in some types of 5 plate holders. The plate developing carrier is provided with means which permit of the entrance and exit of fluid to the carrier in contact with the sensitized plates positioned therein and at the same time exclude 10 light from the compartments of the carrier. After the plates have been subjected to a developing bath for a predetermined period, the developing plate carrier may be brought in contact with a stream of 15 water to quickly wash the developed plates, or the carrier may be placed in another receptacle of running water for the same purpose, after which the carrier with the plates therein may be transferred to another receptacle 20 having a fixed bath. The ordinary steps of developing, washing and fixing may be carried on with the plates remaining in the developing plate carrier thereby precluding all opportunities for injuring 25 the plate, by scratching, abrasion or the like, during the developing process. The plates may be removed from the developing carrier after fixation, or may be washed in the same, as may be preferred.

30 The various parts of the carrier, which are subjected to the chemicals employed in the developing and fixing of sensitized surfaces, are capable of separation from each other to permit washing and drying of the parts, to 35 effectually remove all trace of chemicals previously employed in connection therewith.

In the embodiment of the invention disclosed in the accompanying drawings, the 40 developing negative carrier is shown composed of five separable parts, namely, the outer frame which is disclosed in Fig. 4, the central body portion which is disclosed in Fig. 2 and is adapted to be slidably 45 mounted in the frame of Fig. 4, the upper section shown in Fig. 1 which is connected to the body section of Fig. 2, and the lower section of Fig. 3 which is also connected to the body section of Fig. 2. The usual slides 50 of Fig. 5 are adapted to pass between the frame of Fig. 4 and the assembled parts of Figs. 1, 2 and 3 when positioned within the frame of Fig. 4.

A practical embodiment of the plate carrier provides the body section of Fig. 2 with a frame 1 which may be bent from a single piece of metal to provide wings 1^a, the piece of metal being arranged with its edges in juxtaposition as at 2, the front 1^b and rear 55 1^c sections being secured together by a suitable binding plate 3 at the top, which may have rivets 4, or any other suitable retaining means, and another binding plate 5 at the bottom thereof, said latter plate 5 being 60 shown provided with an inclined face 5^a,

which may serve to maintain the plate or film out of contact with the face 1^b or 1^c of the body. The lower portion of the face plates 1^b, 1^c, may be cut away as at 6 to permit of the entrance of fluid from a recess 70 into another plate compartment formed by the plates 1^b, 1^c, to permit the fluid to act upon the exposed plate to be inserted therein.

Each of the wings 1^a may be provided with suitable openings 8 having an extended 75 portion 9, the metal of which is cut away and bent inwardly to produce a retaining lug 9^a.

The upper section illustrated in Fig. 1 comprises a main plate 10 which may be provided with a plurality of openings 11 which communicate with the plate compartments of the holder thereby permitting air and liquid to escape through said openings. Under this plate 10 there may be provided another 80 plate 12 having a depending flange shown at 12^a on each side of the upper section. This plate 12 is also bent downwardly at the ends to form wings 12^b, and if desired these wings may have inwardly extended flanges 90 12^c. As a continuation of the part 12^b the plate 12 may be extended to form a locking plate 12^d having a slot therein, 15, to be engaged by the lug 9^a of Fig. 2, to effectually lock the top section to the body. To release 95 the top section from the body section pressure may be applied to the plate 12^d to press the same inwardly, and release the lug 9^a from contact with the slot 15. If desired this plate 12^d may be provided also with an 100 inwardly extended flange 14. There may be secured, also, within the plates 10, 12, a suitable retaining strip, 22, which may be of wood or any other suitable material, said retaining strip supporting a plurality of 105 baffles indicated at 23, which permit liquid and air to escape from the interior of the developing plate carrier, or to admit liquid thereto, and at the same time prevent the admission of light to the sensitized surfaces 110 contained within the carrier. To this retaining strip 22 there may be secured a resilient slide engaging member 27 operating to force a strip of fibrous substance, 24, in contact with the ordinary slide 55 (Fig. 5) 115 to exclude light from the interior of the carrier. This fibrous substance may be of felt or any other suitable material and may be secured to the retaining strip 22 if desired. The material from which the resilient slide 120 engaging members 27 are formed may also be bent to produce a protecting flange indicated at 29 between said members 27.

When the upper plate section is secured in its locked position within the body 1, this 125 upper plate section and the body, together with the section illustrated in Fig. 3, may be placed within the frame of Fig. 4, whereupon the upper plate section serves to lock all the members within said frame. This 130

locking means is shown in Fig. 6 as comprising a plurality of angular rods 13, one arm of each rod 13^a extending upwardly and protruding above the plate 10 thereof. The 5 rods are maintained in their extended position by suitable means, such as a spring 26, whereby an end of each rod is caused to protrude through an opening in the plate 12^b at each side of the upper section. This end 10 of the rod is designed to be seated in a recess 50 formed in the upper portion of the frame of Fig. 4 to securely lock the parts in position in said frame. On this upper plate 10 there is shown a substantially similar disk 15 16 having a central aperture 19 through which is passed the ends 13^a of the retaining means, to permit the disk 16 to revolve around said ends. A slotted retaining device 20 is secured to the plate 10 by any suitable 20 means which permits of the rotation of the disk 16, and coöperating with this slotted device 20 is a ring-like-member 21 having disconnected ends, said ends of the ring-like-member 21 being positioned within the 25 slot of member 20 and in contact with the ends 13^a of the resilient retaining device 13, whereby upon compression of the lower portion of said ring-like-member 21, the ends thereof will engage the ends 13^a of the retaining 30 device and retract the other ends of said devices 13 from engagement with the recess 50 and permit of the removal of the interior portion of the plate carrier from its frame.

35 The lower section of the plate developing carrier, which is illustrated in Fig. 3, is shown provided with a base plate 31 which may have upstanding flanges 32 around the sides thereof. The ends of this base plate 31 40 is practically extended to form a retaining plate 32^a which may be provided with side flanges if desired, and which is shown as having a slot 15, similar to the slot of Fig. 1. The retaining plate 32^a is preferably made 45 of resilient material and is designed to be secured within the channeled wings 1^a of the body member 1, to have the retaining lug 9^a engage the slot 15 and lock this base plate to the inner member 1 prior to the insertion 50 of parts 1, 2 and 3 within the part of Fig. 4. The base plate 31 is provided with an aperture 39, to permit of the ingress of any suitable fluid therethrough whereby it may have access to the contents of the carrier.

55 To prevent light from gaining access to the contents of the carrier, there may be provided a suitable housing having the part 34 which serves as means to inclose a baffle member of any preferred construction. In 60 the drawings, the baffle is shown as a plate having a plurality of zig-zag portions, 43, each of the portions being cut away as at 43^a on opposite walls thereof to permit the fluid to pass from one baffle to the next in a tortuous path, and at the same time to prevent

the admission of light from the contents of the receptacle to said baffle. The end walls of the member 34 may be cut away as at 37 to permit the fluid to escape from the baffle device and in contact with the ends 32^a 70 in its path to the interior of the recess and through the aperture 6. If desired the baffle device may be provided with a cover 36 to inclose the same, said cover being cut away at the ends to register with the cut out portion 37.

The frame of Fig. 4 is shown provided with the side members 44 having inturned flanges 45 around all four sides thereof. The base portion 46 is provided with an aperture 80 47 which preferably registers with the aperture 39 in the base of the bottom section of Fig. 3. The side walls 44 may be provided with a retaining lug 54, the purpose of which will be understood, as hereinafter 85 set forth. The upper portion 48 of the frame is made of one piece of metal, and is provided with the usual shoulder 53 which is common to plate holders, the said shoulder being employed to retain the developing plate carrier in position upon the transfer device and it is obvious that this shoulder may be omitted if found desirable or any suitable equivalent employed therefor. The plate 48 may be beveled inwardly as 90 at 52 to insure the guiding of the plate slide 55 of Fig. 5, and the upper inner portion of this member 48 may be turned over as at 49 to securely bind a strip of light excluding material 51. If desired the end plates 100 may be cut away at the top, as at 51^a to provide a seat for the ends of plate 10 of the upper section.

The usual slides, illustrated in Fig. 5 may be provided with an inturned portion 57, 105 and an extended finger portion having a slot 56 therein. When the slide is inserted to its fullest extent, the flange 57 will engage the upper edge of the member of the plate 10, whereupon the disk-like-member 16 can 110 be rotated until a flattened surface 17 thereof is out of register with the slot 56 and an arcuated portion of said disk will pass through said slot 56 and serve to effectually 115 lock the plate holders in their inserted position. If found desirable this disk 16 may have but one or two of such flattened portions whereby a partial rotation of the disk will serve to unlock or lock but one plate slide at a time.

120 It will be obvious that when the plate developing carrier is loaded with undeveloped plates, the entire structure may be deposited in any ordinary receptacle containing developing, washing, or fixing fluid, and that the fluid will pass through the openings 47 or 11 therein and into contact with the chambers which confine the sensitized surfaces.

Having thus described my invention, what 130

I claim as new and desire to secure by Letters Patent, is:—

1. A negative developing carrier comprising a frame, top and bottom members removably mounted on the frame, said top and bottom members having light excluding means which permit of the access of fluid substances to the interior of the frame, slide plates carried by the frame to coöperate therewith and top and bottom members to produce a central chamber within the frame, and a central top portion removably mounted within the frame to divide the chamber into a plurality of compartments.
2. A negative developing carrier comprising an outer frame, a removable interior member mounted within the frame to divide the carrier into a plurality of compartments, and removable end members coöoperating with the frame and interior member.
3. A developing carrier comprising a frame, a plurality of slides for the frame, and a plurality of removable sections connected to form an interior unit adapted to be positioned between said slides and within said frame.
4. A developing carrier comprising a frame, a slide for the frame having a slot near one end thereof, end sections for the frame, one end section having a revoluble disk provided with a flattened portion, said disk coöperating with said slotted slides to lock them in position on the carrier while the flattened portion of the disk permits of the slides being removed from the frame.
5. A developing carrier comprising a frame having end sections and a slide to close the side of the frame, the upper end section being removably positioned within the frame, and means to lock said section to the frame.
6. A developing carrier comprising a frame having end sections and removable slides to close the frame, the removable upper end section positioned within the frame, and means to lock said section to the frame, said means comprising a plurality of spring-actuated rods carried by the end section and adapted to protrude beyond the ends of said section and to engage recesses in said frame.
7. A developing carrier comprising a frame having end sections and slides to close the sides of the frame, the upper removable end section having a portion thereof positioned within the frame, a rotatable disk locking element for the slides, and means to lock said removable end section to the frame, said means comprising a plurality of spring-actuated rods adapted to protrude beyond the ends of said section and to engage recesses in said frame, said rods having upwardly projecting terminals, a contractible element to engage the terminals and simultaneously retract said rods, and which element also controls the locking disk element 65 for the slides.
8. A developing carrier comprising a frame having upper and lower end sections, the removable upper end section having a portion thereof positioned within the frame, a slide, and light excluding means carried by said upper section to coöperate with said slide.
9. A developing carrier comprising a light excluding frame, said frame including a removable upper section having a portion thereof positioned within the frame, a removable slide for the frame, light excluding fabric carried by said upper section and adapted to coöperate with said slide, and resilient means to support said fabric into engagement with the slide.
10. A developing carrier comprising a frame having removable end sections and removable slide sections, the removable upper end section having a portion thereof positioned within the frame and provided with light excluding baffles, said end section having means to permit fluid to flow through said upper end section to the interior of the developing carrier.
11. A developing carrier comprising a light-proof frame and a removable interior member for the frame having a plurality of separable sections, said frame being provided with foraminous end sections having means whereby fluid may enter and escape from the interior of the frame.
12. A developing carrier comprising a frame provided with removable members formed in a plurality of separable sections, some of said sections being provided with fluid ports to permit fluid to flow into the interior of the frame, and light-excluding baffles carried by said sections and positioned adjacent said fluid ports.
13. A developing carrier comprising a frame composed of a plurality of separable end and side sections, and means to lock said sections to the frame to form a unitary structure.
14. A developing carrier comprising a frame and a removable interior member having a plurality of end, side and central separable sections, means to secure said interior member to the frame and means to secure said sections of the interior member to each other and the frame to form a unitary structure.
15. A developing carrier comprising a frame and a removable interior member for the frame having a plurality of separable sections, said interior member and frame forming a light-proof receptacle, said frame and interior member being provided with means to admit fluid to the interior of the carrier, one section of the interior member comprising a body having concave plates

- and side walls to produce a fluid chamber within the frame for a sensitized plate.
16. A developing carrier comprising a frame provided with a removable interior member having a plurality of separable sections, one section including a central projection member and side walls, and means to secure the other sections of the interior member to said side walls.
17. A developing carrier comprising a frame provided with a removable interior member having a central body section, an upper end section and a lower end section, said central end section having a projection and channeled side walls, and means on the upper end section and the lower end section to be inserted in said channeled walls to retain said sections into engagements with the central body section.
18. A developing carrier including a frame, slides for the frame, end members for the frame, and a body section mounted within the frame, said body section being composed of a single piece of metal bent to form extended channeled side walls and a central projection, whereby a plurality of chambers may be formed.
19. A developing carrier comprising a frame provided with a removable interior member having a central body section, an upper section and a lower section, said central section having a projection formed of oppositely positioned concave plates and provided also with extended side walls, means whereby the upper and lower sections may be secured to said side walls, slides cooperating with said interior member and the
- frame to produce developing chambers, and fluid apertures through the upper, central and lower sections of the interior member of the frame to admit fluid to the chambers.
20. A developing carrier comprising a frame provided with a plurality of sections including an interior section and a lower section, the lower section being detachably secured to another of said sections, means to admit fluid to the developing carrier through the lower section, and a light baffle device carried by said lower section.
21. A developing carrier comprising a frame provided with a plurality of sections including a fluid admission section having a removable light baffle element in the base thereof, said baffle element comprising a plate formed to provide a plurality of zig-zag members with a passage between each member.
22. A developing carrier comprising a frame provided with a plurality of sections including a fluid admission section having a removable light baffle element in the base thereof, said baffle element comprising a plate formed to provide a plurality of zig-zag members with a passage between each member and a casing for said zig-zag baffle plates, said casing having apertures therein to permit fluid to pass around said baffles and out of said casing.

In testimony whereof, I affix my signature, in presence of two witnesses.

HARRISON GINDELE.
